UNITED STATES PATENT OFFICE

THOMAS LUND, OF BEVERLY, MASSACHUSETTS, ASSIGNOR TO UNITED SHOE MANUFACTURING CORPORATION, OF PATERSON, NEW JERSEY, A CORPORATION OF NEW JERSEY

FASTENING-SUPPLYING APPARATUS

Application filed July 29, 1927. Serial No. 209,848.

This invention relates to apparatus for supplying such fastenings as nails from a mass in successive groups or loads. Apparatus of this character is employed in connection with machines for attaching heels or other parts of shoes. This supplying apparatus is called upon not only to deliver dependably all the fastenings of a group, but also to thus function when the fastenings differ as to type and size. An object of my invention is to provide for a constant and uniform distribution to the machine supplied of all fastenings, whether they are cut or headed and whatever their length. While by no means limited to this apparatus, my invention is of particular utility in connection with the nail-distributor disclosed in Letters Patent of the United States No. 1,005,303, Pope, October 10, 1911. In this, a rotatable drum elevates nails from a contained mass to downwardly inclined oscillatory raceways delivering to a discharge device, from which, in turn, the nails fall into conduits formed in a holder, which carries tubes leading to the machine supplied.

In such an apparatus as that above indicated, all the raceways which are to share in the delivery of the fastenings must receive from the container a constant supply, and it is desirable that from no raceway shall an excessive number of the fastenings waste, to be returned to the container. A feature of this invention consists of means arranged to alter the points at which the elevating members deliver to the raceways. By a proper selection of the angles of the members, a uniform distribution to the raceways may be attained, and, if it is found that particular portions are receiving too few or too many fastenings, the positions of the elevating members may be changed to correct this. In the specific arrangement herein illustrated, the buckets or elevating members are each adjustable with respect to their angle.

A further feature of the invention involves a control of the delivery from a raceway to the discharge device, as by a change in the rate of travel of the fastenings along the raceway. In the present embodiment of the invention, this change in the travel is ob-

tained by varying the speed of the actuating means by which the raceway is moved. This feature gives a movement of the fastenings over the raceway which will insure their constant presentation to the discharge device for each load, a more rapid oscillation of the raceway, for example, causing long nails to close the space through which they must travel upon the raceway, following the operation of the discharge device and before its succeeding operation, as effectively as short nails. Moreover, the subjecting of the short nails to excessive vibration tending to displace them may be avoided.

It has been found that different forms of fastenings, especially nails, may be more effectively fed along raceways of different cross-sectional form. Cut or blunt pointed nails, for example, are best advanced in grooves of V-shape, while U-grooves are desirable for headed nails or those having relatively sharp points. As another feature of my invention, I render fastening-conveying grooves of diverse forms more readily available for use, by placing these upon the edges of a raceway member and associating therewith means for holding the member with a particular one of the grooves in conveying position. In this way, a plurality of series of raceways in a conveying device may be selectively positioned with a chosen series in conveying relation and readily changed to present another series. There is preferably employed a raceway-bar having conveying grooves converging from their receiving ends to their delivering ends, the opposite grooves being shown as, respectively, of V-shape and U-shape.

An additional feature of the invention involves a conduit, into which the fastenings pass after leaving the raceway, there being combined with such conduit novel means arranged to vary a transverse dimension, as in the direction of travel of the fastenings along the raceway. This change in the dimension of the conduit or conduits, which may be those by which the fastenings are delivered to the tubes leading to the machine at which they are utilized, permits the passage of fastenings of any length within the range oper-

ated upon without danger of the shorter fastenings becoming reversed through being projected from the discharge device into a space intended for the longer. As illustrated, alteration of a conduit is effected by a wall movable within it. When a plurality of raceways deliver to corresponding conduits, as those in a tube-holder, the wall of each conduit may be furnished by a finger 10 extending from a plate movable upon the holder.

One of the many forms which my invention may assume is illustrated in the accompanying drawing, in which
15 Fig. 1 is a side elevation of a nail-distributor embodying my improvements, parts being broken away and in section;

Fig. 2 is a broken perspective view of the lower portion of the nail-way;

20 Fig. 3 is a similar view of the tube-holder, with the partitions mounted in its conduits; and

Fig. 4 is a fragmentary elevation of the forward inner face of the nail-drum.

25 The general structure of the illustrated apparatus is that of the previously mentioned patent, which is particularly designed for the delivery of nails in predetermined groups. My invention, however, may be used in connection with other kinds of fastenings, and when but a single one of these is delivered at a time. Upon a frame 10 is supported a drum 12 rotated from a counter-shaft 14. Nails contained in the drum are elevated by a series 30 of buckets 16 surrounding the periphery and are dropped upon an inclined nail-way 18, in which are parallel raceways or grooves, the lower portions of which are formed in bars 20. Along these raceways, the nails are conveyed as a consequence of oscillation imparted to the nail-way through connections to the shaft 14. The terminal nails on the raceways are acted upon by a perforated discharge-roll 22. This, with the assistance of a stop-bar 45 24, arrests the progress of the successive loads of nails and then is oscillated to deliver said loads into conduits 26 formed vertically in a holder 28. Each conduit is continued by a tube 30 leading to the machine to be supplied 50 with nails.

For any particular angle at which the buckets 16 lie with reference to the path through which they revolve, they will tend to spill the contained nails upon the nail-way 55 at the same point. Consequently, if all are mounted in the same angular relation, as is customary, certain of the conveying raceways will be situated directly under the maximum flow from the buckets and will receive many 60 more nails than the companion raceways. To assure a supply to all the raceways, the delivery from similarly positioned buckets must be in such quantity that the necessary number will fall upon the less favored. Under these circumstances, a great number will

overflow from the grooves better supplied and waste back to the drum, to be again elevated. I reduce this repeated elevation of the nails by arranging the buckets to spill at different points by the location of their nail-carrying surfaces at different angles. They are preferably made adjustable about axes substantially parallel to that about which the drum rotates by being mounted upon stems 40, which may turn in openings about the edge 75 of the inner head of the drum. A finger-piece 42 upon the exposed portion of each stem permits the operator to turn the bucket, which may then be locked in place by a nut 44 threaded upon the stem and bearing against the head of the drum. With this organization, the buckets may be so positioned as to obtain the desired uniformity of distribution across the nail-way. A relation which I have found efficacious is indicated in Fig. 4. 80 Here, the leading bucket A of a set of three retains the nails longest and therefore delivers most to the distant side of the nail-way. The second bucket B drops its nails sooner upon the center raceways, while the third bucket C covers best the nearer grooves. It will be observed that the buckets lie at progressively smaller angles with respect to radii of the drum passing through the axes of 85 their stems. By means of the adjustment of the buckets, their angles may be varied according to the nail-way-grooves in use or the character of the fastenings which are being supplied.

90 After delivery to the grooves of the nail-way 18 by the drum, the nails advance at a rate depending upon the rate of oscillation of the nail-way and therefore the speed of rotation of the counter-shaft 14. Short nails are most certainly conveyed by the grooves if the movement of the nail-way is relatively slow. More rapid oscillation tends to displace them, and they may fail to enter the openings in the roll 22. On the other hand, with a rate of movement suitable for the short nails, the longer nails may not be advanced at a sufficient speed to reach the roll after the discharge of the preceding load. In this way, every alternate load may be missed. I have so organized the apparatus 100 that the nail-way movement may be at the rate best suiting the length of nails operated upon. Situated in the base of the frame 10 is a change-speed mechanism X. This may be 105 of any desired type, being herein indicated as that well-known form in which a belt or chain 46 operates over pairs of oppositely inclined conical pulleys 48, 48 upon shafts 50 and 52. Adjusting mechanism, controlled 110 by a hand-wheel 54, allows the pulleys of one pair to be separated from each other, while those of the other pair are brought nearer together. This variation in the effective diameter of the driving surfaces of the cones 115 permits the power applied to the shaft 50 by 120

a belt 56 to be transmitted to the counter-shaft 14 through the belt 46 and a belt 58 at a greater or less speed, which may be controlled in fine gradations. With the resulting change in the speed of the shaft 14, the rate of oscillation of the nail-way is correspondingly altered and, therefore, the rate of travel of the nails along the raceways. The nails used chiefly in the attachment of shoe-heels or bases are the cut type, these being angular in cross-section and having blunt points and little or no head. Nails with substantial heads, which are pointed and circular in section, are employed for the attachment of rubber lifts. The first-mentioned type is most effectively conveyed to the discharge-roll in an orderly series, arranged end to end without overlapping, by a groove which is V-shaped in cross-section. The headed nails advance best, without tendency to override one another, in grooves which, to a considerable extent, correspond in cross-section to the curvature of the heads. The grooves for these nails are customarily of U-section. I provide for the ready availability of either form of groove in my improved nail-distributor by furnishing the bars 20, which constitute the lower portion of the nail-way 18, with a V-groove 62 in one edge and a U-groove 64 in the opposite edge. These grooves converge from the upper receiving end of each bar, where they are considerably spaced vertically, to the lower delivering extremity, at which they are in close proximity. The lower portions of the bars 20 are shown as mounted and correctly spaced from one another upon a rod 66 extending through registering openings in the bars. Thimbles 68 separate the bars from one another upon the rod, and this assembly is held together by nuts 70 operating upon threaded ends of the rods and bearing against the faces of the outer bars. A support for the rod upon the nail-way frame is furnished by opposite aligned screws 72, 72 threaded through said frame and entering bores in the ends of the rod. The upper extremity of each bar has separated arms 74, 74, each arm entering a groove in a spacing and clamping bar 76. Each bar 76, which is individual to one of the sets of grooves, has threaded through its opposite extremities screws 78. Those screws which are upmost bear against projections 80 from opposite sides of the nail-way frame. Upon advancing these screws, the recessed ends 82 of the bars are forced against a correspondingly formed portion of the upper section 84 of the nail-way. In this upper section farthest removed from the discharge device, the cross-sectional form of the raceways is less important and may remain unchanged. It is herein shown as V-shaped. It will be seen that, to change from one set of grooves to the other, it is only necessary to loosen the upper screws 72 and 78, reverse

the lower section, and again set the screws 72 to engage the rod 66 and the now active screws 78 to clamp the bars at 74 against the upper section.

The passages or conduits 26 in the holder 28 leading the nails falling from the discharge-roll 22 to the tubes 30, must be of such width at their upper portions that the longest nails may enter without interference. Yet, with this size, shorter nails projected forward by the turning of the roll may be reversed, so that they fall with the wrong end first. I have so arranged the tube-holder that the transverse dimension of the upper portion of the conduits, taken in the direction in which the nails are thrown from the roll, may be adjusted to correspond to the length operated upon. Extending along the outer side of the upper face of the holder is a plate 90, from which fingers 92 depend within the conduits 26. The width of these fingers is such that substantially complete partitions are furnished across the top of the conduits. At the outer edge of the plate is a vertical flange 94, reinforced by a thin bar 96. The plate and its fingers are guided for horizontal movement by pins 98 projecting from the holder through openings in the bar 96. This bar is slotted to enter grooves 100 in screws 102 threaded into the holder. By turning the screws, the partitions 92 may be adjusted toward and from the discharge-roll. When nearer to the roll, shorter nails, one of which appears at N in Fig. 3, are properly received without having an opportunity to become reversed in falling. An increase in the width of the conduits by carrying the partitions away from the discharge-roll adapts said conduits for the reception of longer nails.

Having described my invention, what I claim as new and desire to secure by Letters Patent of the United States is:

1. In a fastening-supplying apparatus, a series of raceways, a rotatable container for fastenings, fastening-elevating members carried by the container and movable across the raceways for delivery thereto, and means arranged to vary the points at which the elevating members deliver to the raceways.
2. In a fastening-supplying apparatus, a rotatable drum for delivering fastenings, fastening-elevating members variable in position about axes extending longitudinally of the drum, and means for securing the members in different positions.
3. In a nail-distributor, a series of raceways, a nail-drum rotatable in proximity to the receiving ends of the raceways, nail-elevating buckets each arranged for angular adjustment upon the drum, and means for securing each bucket in its adjusted position.
4. In a nail-distributor, a nail-way, a nail-drum rotatable in proximity to the receiving end of the nail-way, nail-elevating buckets each having a threaded shank rotatable in a

wall of the drum, and a nut upon each shank for engagement with the drum-wall.

5. In a fastening-supplying apparatus, a movable race-way, actuating means therefor, and means arranged to vary the speed of the actuating means.

6. In a fastening-supplying apparatus, an oscillatory raceway, actuating means therefor, a source of power, and change-speed mechanism interposed between the source of power and actuating means.

7. In a fastening-supplying apparatus, an oscillatory raceway, a discharge device to which the raceway delivers, and means arranged to control the rate of oscillation of the raceways and thus the delivery therefrom to the discharge device.

8. In a fastening-supplying apparatus, an oscillatory raceway, a discharge device to which the raceway delivers, and means arranged to vary the rate of movement of the raceway and thereby the rate of travel of the fastenings upon the raceway toward the discharge device.

9. In a nail-distributor, an oscillatory nail-way, an oscillatory discharge device to which the nail-way delivers, a rotatable shaft provided with connections for reciprocating the nail-way, a source of power, and change-speed mechanism connected to the source of power and to the shaft.

10. In a nail-distributor, a frame, a nail-way mounted to move upon the frame, an actuating shaft for the nail-way journaled in the frame, and change-speed mechanism situated in the base of the frame and connected to the shaft.

11. In a fastening-supplying apparatus, a device having a plurality of sets of fastening-conveying grooves, and means arranged to hold a selected set of the grooves in conveying position with an associated set in inactive position.

12. In a fastening-supplying apparatus, a raceway member having in its edges fastening-conveying grooves differing in cross-sectional form, and means arranged to hold the member with a particular one of the grooves in conveying position.

13. In a fastening-supplying apparatus, a raceway member having along one edge a groove curved in cross-section and along the opposite edge a groove angular in cross-section, and means arranged to hold the member with either groove in conveying position.

14. In a fastening-supplying apparatus, a raceway-bar having fastening-conveying grooves converging with respect to each other from their receiving ends to their delivering ends.

15. In a fastening-supplying apparatus, a raceway-bar having at its opposite edges a U-shaped groove and a V-shaped groove converging from their receiving ends into close

proximity to each other at their delivering ends.

16. In a fastening-supplying apparatus, a support, a series of raceway-bars having grooves in their opposite edges, a member upon which the bars are mounted, and means carried by the support and being movable to engage and release the mounting member.

17. In a fastening-supplying apparatus, a support, a series of raceway-bars having grooves in their opposite edges, a member upon which the bars are mounted, means carried by the support for engaging the mounting member, and means for fixing the bars against movement on the engaging means.

18. In a fastening-supplying apparatus, a support, a series of raceway-bars having grooves in their opposite edges, a member upon which the bars are mounted, means carried by the support for engaging the mounting member, and means individual to the set of grooves in each of the edges for fixing the bars against movement on the engaging means.

19. In a fastening-supplying apparatus, a support, a series of raceway-bars having grooves in their opposite edges, a rod connecting the bars, screws threaded through the support and upon which the rod is mounted, and screws carried by the bars and engaging the support.

20. In a fastening-supplying apparatus, a support, a series of raceway-bars having grooves in their opposite edges, a rod connecting the bars, means extending from the support and upon which the rod is mounted, and oppositely extending screws carried by the bars for engagement with the support.

21. In a fastening-supplying apparatus, a raceway, a conduit through which the fastenings pass after leaving the raceway, and means arranged to vary a transverse dimension of the conduit and retain it in its adjusted relation during the delivery of the fastenings from the raceway.

22. In a fastening-supplying apparatus, a raceway, a conduit, means for discharging fastenings from the raceway into the conduit, and means arranged to vary the width of the passage through the conduit in the direction in which the fastenings are discharged.

23. In a fastening-supplying apparatus, a conduit through which fastenings are discharged from the apparatus, and a wall along which the fastenings travel during their discharge, said wall being movable in the conduit.

24. In a nail-distributor, a raceway, a discharge device to which the raceway delivers, a conduit into which the nails fall from the discharge device, and a wall forming a side of the conduit and movable toward and from the discharge device.

25. In a nail-distributor, a plurality of raceways, a tube-holder having a passage cor-

responding to each raceway, and a plate movable upon the holder and provided with a finger extending into each passage.

26. In a nail-distributor, a plurality of raceways, a tube-holder having a passage corresponding to each raceway, a plate movable upon the holder and provided with a finger extending into each passage, and a screw threaded into the holder and arranged to move the plate.

10 In testimony whereof I have signed my name to this specification.

THOMAS LUND.
